(57) **CLAIM**

The ornamental design for a corner computer desk, as shown and described.

DESCRIPTION

FIG. 1 is a perspective view of the new design;

FIG. 2 is a side view thereof;

FIG. 3 is a top view thereof;

FIG. 4 is a front view thereof;

FIG. 5 is a rear view thereof; and,

FIG. 6 is a bottom view thereof.

The broken lines are for environmental purposes only and form no part of the claimed design.
